SALIVA EJECTOR

Barrett Lumian, Brookline, Mass.

Application November 5, 1947, Serial No. 784,099

1 Claim. (Cl. 32—33)

1

This invention relates to saliva ejectors of the type used in removing excess moisture from the patient's mouth during dental work, and pertains more particularly to improvements in the mouth piece of the conventional saliva ejector.

The mouth pieces of saliva ejectors heretofore generally used by dentists have consisted of rigid, crook-shaped tubes, usually of metal but sometimes made of glass or plastic material. The regular rigid mouth pieces, which are removably attached to flexible tubes leading to the dental cuspidor or drain, have been made in one or two standard sizes, and no attempt has been made to produce a mouth piece which is capable of fitting all mouth sizes, or even a set of graduated sizes which would imperfectly fulfill that purpose.

For proper efficiency of operation and comfort to the patient, the saliva ejector should rest upon the lower front teeth of the patient with its perforated tip approximately $\frac{1}{8}$ " above the level of the soft tissues constituting the floor of the mouth. If the tip rests upon the floor of the mouth, the weight of the mouth piece and the connecting conduit presses the tip into the soft tissues and these tissues are drawn into the perforated tip by the suction of the saliva ejector, clogging the inlet and causing considerable discomfort to the patient. The dentist's efficiency is thus impaired because the mouth is not sufficiently dry and because the patient's discomfort induces movement of the tongue and mouth, and, if the mouth is very shallow, the crooked end of the mouth piece is elevated above the lower teeth and obstructs free access to the mouth. Moreover, removal of a clogged mouth piece frequently causes laceration of the soft tissues and consequent bleeding which is distressing to the patient, and interferes with further dental work.

When, on the other hand, the standard mouth piece is used in a relatively deep mouth, its crooked portion is supported by the lower teeth and the apertured tip does not reach sufficiently close to the floor of the mouth to permit saliva to be completely suctioned off. Dental efficiency is again impaired because the mouth is not dry enough for proper preparation of cavities, insertion of filling material and the like.

When it is appreciated that the depth of an adult mouth may vary from one-half inch in a very shallow mouth to more than two inches in a very deep mouth, and that the mouths of young children are even more shallow, the problem of efficient and comfortable fitting of the

mouth piece obviously cannot be achieved by the standard saliva ejectors.

It is accordingly the principal purpose of the present invention to provide an adjustable mouth piece which will correctly and comfortably fit a patient's mouth regardless of its depth or conformation, and which will reach to any desired area in the mouth, anterior or posterior, without sacrifice of efficiency.

To this end, the improved mouth piece comprises a rigid, crooked tube and a sleeve of rubber or other relatively soft and flexible material which is adjustably slidable along the end portion of the rigid tube and is provided with an apertured tip which may be properly located at the desired position in the patient's mouth, according to the effective length of the adjusted sleeve. The sleeve frictionally engages the rigid tube so that its adjusted position will be maintained while in use, but may be readily removed for sterilization and reapplied and readjusted for another patient.

The adjustable sleeve is of sufficient length to cover the crook of the rigid tube when used for a deep mouth, so that the soft sleeve rather than the hard metal or other rigid material of the tube rests upon the lower front teeth of the patient, thereby protecting the teeth, adding to the patient's comfort, and avoiding any damage to the teeth or tube by biting which frequently occurs with young patients.

A recommended embodiment of the invention is illustrated in the accompanying drawings, but it will be understood that the structural details of the devices herein shown and described may be varied without departing from the essence of the invention as defined in the appended claim. In the drawings,

Fig. 1 is a side view of the improved saliva ejector as applied to a shallow mouth;

Fig. 2 is a side elevation of the improved mouth piece, partly in section, showing the sleeve adjusted for a deep mouth; and

Fig. 3 is a similar view showing the sleeve adjusted for an average mouth, and also illustrating an optional form of tip at the end of the mouth piece.

The saliva ejector comprises a tube 11 of metal or other rigid material, having a relatively short curved or crooked portion 12 terminating in a serrated tip 13, and a collar 14 at its opposite end which is fitted into the flexible hose or conduit 15 leading to the conventional dental cuspidor which is equipped with a suction pump for

drawing saliva from the mouth through the ejector.

In the form illustrated in Figs. 1 and 2, the adjustable sleeve 16 of rubber or other relatively soft and flexible material, has a close slidable fit over the end of tube 11, extends beyond the end of the tube, and is provided at its free end with a rigid tip having a stem 17 embraced by the sleeve end and a head suitably apertured at 19 for withdrawing saliva from the bottom of the mouth. The sleeve has vents 20 rearwardly of the stem 17 to allow passage of air through the ejector in case the head openings should become accidentally clogged. The sleeve 16 fits closely around the tube 11 so that it will maintain the adjusted position fixed by the dentist, but is readily applied and removed by hand. For easy application, the sleeve should be dipped in water before it is pushed onto the rigid tube.

In the optional form shown in Fig. 3, the separate, headed tip member is omitted, and the tip end of the rubber sleeve 21 is closed and provided with openings 22 in its wall.

In either form, the sleeve applicator may be moved along the tube 11 until the effective length of the mouth piece is adjusted to the size of the patient's mouth and meets the requirements of the dental work to be performed. Figs. 1, 2 and 3 indicate approximate positions of the sleeve for shallow, deep and average mouths respectively, when the tip of the applicator is to be located in the anterior portion of the mouth.

The improved mouth piece avoids the objectionable aspects of the standard saliva ejectors now on the market, and satisfies the requirements of a universal mouth piece which may be adjusted for use with all dental patients and afford maximum comfort to the patient and maximum efficiency by the dentist or technician. Correct adjustment of the sleeve may be deter-

mined by inspection or experiment; but, if the mouth piece is incorrectly adjusted and reaches the floor of the mouth, the flexibility of the rubber sleeve allows its tip to rise and fall with movement of the mouth, thus avoiding uncomfortable pressure on the soft tissues.

I claim:

A saliva ejector having a mouth piece comprising a crooked, rigid tube, and a relatively soft and flexible sleeve fitting closely over the outer end portion of the tube and slidable thereon, whereby the effective length of the mouth piece may be varied by manually adjusting the position of the sleeve with respect to the tube, the crooked portion of the mouth piece being adapted to rest upon the lower teeth of the patient, and the sleeve having sufficient length to cover the crook of the tube and protect the teeth from contact with the rigid tube when the sleeve is in any adjusted position, the outer end portion of the flexible sleeve extending beyond the outer end of the rigid tube and having an apertured tip insertable in the mouth of the user.
